Primary Examiner — April Rivas(74) **Attorney, Agent, or Firm — Heedong Chae; Lucem, PC**(57) **CLAIM**

The ornamental design for a case for a charging case, as shown and described.

DESCRIPTION

FIG. 1 is a front perspective view of a case for charging case showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded front perspective view of the case for charging case.

The broken lines throughout the drawing figures depict portions of the case for charging case that form no part of the claimed design.
